ANIMAL FIGURE HAND PUPPET

Marie H. Frost, Wheaton, and Russell B. Odell, Elgin, Ill., assignors to David C. Cook Publishing Company, Elgin, Ill.

Filed Feb. 16, 1971, Ser. No. 115,941

Term of patent 3½ years

Int. Cl. D21—01

U.S. Cl. D34—2

FIG. 1 is a front plan view of an animal figure hand puppet embodying our new design;

FIG. 2 is a front plan view similar to FIG. 1 but showing the movable parts of the eyes of the animal figure hand puppet in a different position from that in which they are shown in FIG. 1;

FIG. 3 is a rear plan view of our new design;

FIG. 4 is a top plan view; and

FIG. 5 is a bottom plan view.

We claim:

The ornamental design for an animal figure hand puppet, substantially as shown and described.
